UNITED STATES PATENT OFFICE

96,448

DESIGN FOR AN ELECTRIC GRILL

**Fredrick David Chapman, Evanston, Ill., assignor
to Montgomery Ward & Co., Incorporated,
Chicago, Ill., a corporation of Illinois**

Application May 27, 1935, Serial No. 57,043

Term of patent 7 years

To all whom it may concern:

Be it known that I, Fredrick David Chapman, a citizen of the United States, residing at Evanston, in the county of Cook and State of Illinois, have invented a new, original, and ornamental Design for an Electric Grill, of which the following is a specification, reference being had to the accompanying drawing, forming a part hereof.

In the drawing,
Fig. 1 is a perspective view of an electric grill showing my new design;

Fig. 2 is a side elevational view thereof;
Fig. 3 is a top plan view of the electric grill.

I claim:

The ornamental design for an electric grill, as shown.

FREDRICK DAVID CHAPMAN.
